US0D1066296S

(12) **United States Design Patent** (10) **Patent No.:** **US D1,066,296 S**
(45) **Date of Patent:** **** Mar. 11, 2025**

(54) **SET OF REMOTE CONTROL PAGE TURNER
AND CORRESPONDING RECEIVER**

(71) Applicant: **Tianjin Changqingshu Trading Co., Ltd.**, Tianjin (CN)

(72) Inventor: **Yilin Xiao**, Linqing (CN)

(73) Assignee: **Tianjin Changqingshu Trading Co., Ltd.**, Tianjin (CN)

(**) Term: **15 Years**

(21) Appl. No.: **29/923,438**

(22) Filed: **Dec. 29, 2023**

(51) LOC (15) Cl. **14-03**

(52) U.S. Cl.

USPC **D14/218**

(58) **Field of Classification Search**

(57) **CLAIM**

The ornamental design for a set of remote control page turner and corresponding receiver, as shown and described.

DESCRIPTION

FIG. 1 is a top, front and right side perspective view of a set of remote control page turner and corresponding receiver showing my new design;

FIG. 2 is a bottom, rear and left side perspective view thereof;

FIG. 3 is a bottom, front and right side perspective view thereof;

FIG. 4 is an alternative perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof; and,

FIG. 10 is a bottom plan view thereof.

1 Claim, 10 Drawing Sheets
